JIG FOR TREATING MATERIALS OF
DIFFERENT SPECIFIC GRAVITIES

Edmond Harvengt, Moustier-sur-Sambre, Belgium, assignor to Link-Belt Company, Chicago, Ill., a corporation of Illinois

Application May 16, 1947, Serial No. 748,428
In Belgium May 22, 1946

11 Claims. (Cl. 209—457)

1

This invention is directed to an improvement over the device disclosed in my copending application Ser. No. 10,756, filed February 25, 1948.

The invention relates to apparatus for treating materials containing particles of different specific gravities such as coals, ores and the like, in which these materials are supported on a sieve or grid and are classified and eventually separated from one another by means of liquid pulses, especially pulses due to the movements of a reciprocated piston or diaphragm.

Apparatus of the kind aforesaid are common in the art and the operation thereof is well known. However as previously devised imperfect results only are obtainable in practice as well from the point of view of the classing of the materials as from the point of view of the separation thereof, owing, amongst other, to the wide variability of these materials as well as regard the quantities to be treated as to their composition.

In fact if, any other things remaining unchanged, there is a change in the quantity of the materials to be treated, the previously obtained classing is not longer effected in the same way, and where a separation is taking place, the separated portions are not longer the same as well in quantity as in composition.

The same occurs if, under similar conditions, the composition of the materials to be treated becomes modified.

In order to take care of the variability, as to the quantity and composition, of the materials to be treated, it is of interest to be able to modify, either alone or in combination, the following conditions or factors of the treatment:

(a) The regimen of advance and discharge of the materials, or at least of a class or category of the materials occupying the sieve or grid;

(b) The quantity of the materials or at least of a class or category of the materials occupying the sieve or grid;

(c) The area of the sieve or grid on which are spread the materials occupying the sieve or grid;

(d) The effect of the pulses and/or of the liquid currents set up in the apparatus, on the materials occupying the sieve or grid or on the materials discharged from the sieve or grid, or on both the one and the other.

In order to answer these requirements, in accordance with the invention apparatus of the kind specified are provided with certain means and arrangements, amongst which:

A sieve or grid constructed to receive as well a horizontal position as sloping positions on either side of this horizontal position;

2

Means for retaining on the sieve or grid, as a kind of fixed bed, a predetermined and adjustable quantity of the materials, such as a movable and adjustable weir provided at that end of the sieve or grid which is remote from the feed of the materials;

Means for modifying the useful or working area of the sieve or grid, such as a member suitable for overlapping and rendering ineffective a portion of such area;

Means for conditioning the liquid pulses and, or the liquid currents set up in the apparatus, in order to modify the actions thereof on the materials occupying the sieve or grid or on the materials discharged or coming from the sieve or grid, or both, such means comprising, among other things, one or more governing partitions, which may include a movable part or be combined with movable members arranged within the passage or passages leading towards the sieve or grid and/or towards the discharge from this sieve or grid and provided by said partition or partitions;

Where desirable, means may be provided to compensate entirely or to any desired extent the action on the materials occupying the sieve or grid and on the discharge of the nonworking or suction strokes of the piston or diaphragm causing the liquid pulses where a piston or diaphragm is provided for generating said liquid pulses.

And in order to enable the manner in which the above arrangements may be practically carried out, may be well understood, certain of their preferred embodiments together with certain of their preferred applications, will be described hereafter with more details and with the aid of the annexed drawings, such embodiments and applications being by way of example only.

In the drawings:

Figure 1 is a diagrammatical elevation and sectional view of a sorting and separating apparatus having certain features of the invention applied thereto;

Figures 2, 3 and 4 show, similarly, other arrangements;

Figure 5 shows diagrammatically a plant comprising the association of apparatus of the kind illustrated in Figs. 1 to 4 with a washing trough;

Figure 6 shows diagrammatically a similar plant relating to another application of the invention.

Referring first to Fig. 1, 1 designates a box having at 2 feeding means for the materials to be treated—which may be crude materials or materials previously submitted to a classing or sorting

operation; 3 designates a sieve or grid on which takes place the classing of the materials with, as the case may be, a separation of the heavy portions passing through the sieve or grid to reach the bottom of the box 1, the light portions passing over a weir 4, which may be adjustable especially as to the height, to reach a trough or any other location.

5 designates a piston arranged within a housing 6 of the box 1, and actuated for reciprocation in said housing by means of any suitable mechanism such as an eccentric 7 and a rod arrangement 8.

9 designates a discharge device—for continuous or intermittent discharge—conveniently for example a pocket discharge device as shown, for the heavy portions of the materials separated on the grid or sieve 3, and 10 is an adjustable liquid supply suitable for generating within the box 1 and through the sieve or grid 3 ascending currents of adjustable intensity.

An arrangement as described and the operation thereof are well known and do not require more extensive explanations.

To appropriate such a device for a wide diversity in quantity and composition of the materials, in accordance with one feature of the invention the sieve or grid 3 is arranged so as to be able to take various slopes relative to the horizontal position and on either side of the horizontal, by supporting said sieve or grid on a shaft 11 journaled in the walls of the box 1 and located in the example as illustrated at or near the sieve or grid end which is remote from the feed 2 of the materials. This shaft 11 is connected to any suitable operating mechanism, for example a mechanism such as illustrated and comprising a lever 12 made integral for rotation with the shaft 11. A rod 13 pivoted on the lever 12, and a portion of the rod 13 is screw threaded and engaged within the screw threaded bore of an operating hand wheel 14 occupying a fixed position in the direction of the axis of the screw. With such an arrangement a rotating movement of the wheel 14 in the appropriate direction will cause the sieve or grid 3 to reach any desired sloping position on either side of the approximately horizontal position illustrated. However the shaft 11 could be located at the other end of the sieve.

It will be appreciated that by so modifying the slope of the sieve or grid 3, all other things remaining the same, the regimen of advance of the materials on the sieve or grid will be modified. An increase in the upward slope or a decrease in downward slope of the grid or sieve in the direction of the advance of the materials will slow such advance while to the contrary a decrease in the upward slope or an increase in the downward slope in said direction will enhance said advance. It will also be appreciated that by modifying the slope of the sieve or grid, all other things remaining the same, the distribution of the bed of materials will be modified along the sieve with as a result a change in the distribution of the actions of the liquid impulses and liquid currents due to the active strokes of the piston 5 and the liquid supply 10. Thus, if from any position of the sieve or grid 3 the slope thereof is modified so as to increase its upward incline or reduce its downward incline in the direction of advance of the materials, the distribution of the bed of materials will be modified, resulting in a relative increase of the depth of the bed along the sieve or grid which is a maximum at the entrance of the sieve or grid and a simultaneous relative decrease, along the sieve or grid, of the

actions on the bed of materials of the liquid impulses and liquid currents which is a maximum at the entrance of said sieve or grid.

Naturally, reverse results will be obtained with 5 a change of opposite sense in the slope of the sieve or grid.

It may easily be seen that the changes in the regimen of advance of the materials along the 10 sieve or grid and in the actions of the liquid impulses and the liquid currents on the materials occupying the sieve or grid combine one with another to improve at least the separation since, while all other things remain the same, to a lesser depth of the bed will correspond an increasing effect of the liquid impulses and liquid currents with a more marked separating action 15 on the light particles.

To modify the area of the sieve or grid occupied by the materials, in accordance with another 20 feature of the invention there is arranged between the feed 2 and the sieve or grid 3, a plate 15 which is rendered movable along said sieve or grid, for example by associating said plate with a plate 16 sliding within a guide 17, the plate 15 being moreover hinged to the plate 16, as 25 at 18, to allow for the aforesaid changes in slope of the sieve or grid 3. The plate 16 itself or, as illustrated the hinge 18, is associated with a drive such as the driving screw 19 or a similar drive, suitable for moving forward and backward the plate 15 on the face of the sieve or grid 3.

This results in the possibility of modifying as 30 desired the useful or working area of the sieve or grid 3 with the result of a simultaneous change 35 in the action of the liquid impulses and liquid currents upon the materials occupying the sieve or grid.

Thus if the position of the plate 15 is changed 40 by moving same to the right in the figure, the useful or working area of the sieve or grid 3 is reduced in a substantially proportional manner and if, the other things remaining the same, the liquid impulses and liquid currents due to the piston 5 and to the liquid supply 10 are not 45 altered, the action of said impulses and currents upon the materials occupying the useful area of the sieve or grid 3 will be reinforced in a corresponding manner.

It will further be seen that by moving the 50 plate 15 forward or backward along the sieve or grid, the distribution or arrangement of the bed of materials on the occupied area of the sieve will be modified with results which are similar to those indicated in relation with the changes in the slope of the sieve or grid.

For example, with all other things remaining 55 the same, if the plate 15 is moved so as to reduce the useful area of the sieve or grid, the distribution of the bed will be modified in the sense of a relative increase in the depth of the bed along the occupied area which is a maximum at the entrance of said area. A reverse result will be obtained when the plate 15 is moved so as to increase the useful area occupied by the materials on the sieve or grid. The possibility is thus provided to enhance or attenuate by this means the effects of a change in the slope of the sieve or grid 3, thus providing by combination further practical possibilities in the conditioning of the treatment of materials on the sieve or grid.

Furthermore, when the slope of the sieve or grid 3 is modified, the slope of the plate 15 is changed in a simultaneous manner, and it should be observed that the change in the position of the plate 15 has a resulting action which concord

with that of changes in the sieve or grid position, thus enhancing the actions obtained by modifying the slope of said sieve or grid.

In arrangements similar to the one described, in which the liquid impulses are generated by the movements of a reciprocating piston 5, the non working ascending strokes of the piston may result in a suction being applied on the materials occupying the sieve or grid 3 which may be undesirable for certain applications.

This suction effect may be avoided entirely or by part by introducing liquid within the box 1 during the non working strokes of the piston 5, for example in the manner illustrated in the figure in which a sliding valve 20 is connected on the one hand with any suitable source of liquid, such as a branch of a distribution main as shown by part at 21, and on the other hand with the space, suitably bounded by a cover 22, above the piston 5 within the housing 6, and further with the box 1, through the passage 23 opening into the box below the level of the sieve or grid 3.

The sliding valve 20 is actuated by means of the eccentric drive 7, of the piston 5, through the intermediary of a crank disc 24 and a connection 25, the arrangement and adjustment being such that during the working or downward strokes of the piston 5, the sliding valve opens the communication between the liquid source 21 and the space of the housing 6 above the piston 5, while such communication is cut out and the sliding valve opens the communication between said space and the box 1 during the non working or upward strokes of the piston 5. The liquid stored above said piston thus passes into the box 1 and reduces or suppresses any suction effect on the material bed located on the sieve 3 due to such movements of the piston. It is to be understood that the drive of the sliding valve, as well as the features proper of said valve may be modified to secure any desired degree of compensation of the suction effect due to the movements of the piston 5.

Referring to Fig. 2, the features already specified as well as certain other arrangements of the invention have been applied to an apparatus for the separation of materials of different densities such as coals, ores and the like comprising an oscillating grid or sieve with a controlled discharge of materials or at least of certain classes or categories thereof at the end of this sieve or grid, the oscillating movements of the sieve and eventually the operation of the device controlling the discharge being timed with the movements of the piston generating the liquid impulses in the apparatus.

The figure shows the box 1, the feed 2, the piston 5, its housing 6 and its drive 7-8; the plates 15-16 hinged at 18, the guide 17 and the drive 19, as well as the device designated by the references 20 to 25 and suitable to ensure the avoidance of the suction effects on the materials of the bed during the ascending strokes of the piston 5, and which are similar and the operations of which are the same to those of the example of Fig. 1.

The sieve or grid 3 is pivotally united to rods 26 for connection with shafts 27, of which one at least is journaled in the walls of the box 1 and one at least may be actuated for oscillatory movements by a suitable mechanism, for example a mechanism including a lever 28 made integral for rotation with the driven shaft 27 and a drive 29 having an adjustable connection such as 30

with the eccentric drive 7-8 for the piston 5, the arrangement being such that the sieve or grid 3 moves downwards and backwards (towards the left) when the piston 5 performs its active or descending stroke, while said sieve or grid moves upwards and forwards when the piston 5 performs its non working ascending stroke.

On the other hand, the control device for the discharge of the products from the sieve or grid 3, arranged opposite the free end of said sieve or grid, comprises a system of plates 31 and 32 hinged together on a common shaft 33 and hinged on a shaft 34 journaled in the walls of the box 1. The plate 31 comprises a shaft 35 connected, by means of rods or links 36 hinged together at 37, to a shaft 38 journaled in the walls of the box 1. The hinge 37 is connected, through a rod or link 39 to a driving mechanism 40, for example comprising a screw or the like cooperating with a hand wheel enabling the position of said hinge to be modified and thereby the basic adjustment of the control device for the discharge 31-32 to be effected.

The control device for the discharge may be such as at present described, or alternately a lever of adjustable operative length 41 may be secured to the shaft 34 while a suitable point of said lever is connected directly or indirectly, through a driving arrangement 42, to the driving arrangement for the piston 5, in such a way that the device controlling the discharge from the sieve performs movements in concord with those of the piston 5, that is the common hinge 33 moves downwards and upwards while the piston 5 ascends and descends within its housing 6 respectively.

An adjustable liquid supply is provided at 43 and as in the example of Fig. 1, the lower end of the box 1 is connected to a discharge device of any suitable type, for example a pocket discharge device 9 (Fig. 1) operating continuously or intermittently.

In operation, when the materials in either mixed condition or already more or less sorted, coming at 2, pass on the grid or sieve 3, which is oscillated and associated with a device as described for controlling the discharge, owing to the alternative movements of the piston 5 these materials are subjected to liquid impulses, while they are simultaneously influenced by the movements imparted to the sieve or grid and, as the case may be, by the generally ascending currents issued from the liquid supply 43. The liquid impulse caused by the downward movement of the piston acts on the bed to reject upwards the grains or particles of lesser density, the denser grains or particles reaching the or remaining in the lower layers. At the same time the inertia of the particles or grains especially the denser one, does that while effecting its downward movement, the sieve or grid moves relatively to said grains or particles, towards the left, with the result that the materials are in fact caused to move towards the right end, of discharge, of the sieve or grid, which movement is assisted, or even caused, by the plate 15 acting as a stop for the materials, especially those of the lower layers, preventing them from moving towards the left with the sieve or grid should they have a tendency to follow the direction thereof in such a direction. An effective discharge is thus obtained at the right end, of the grid or sieve, the denser particles or grains passing within the box 1, between the end of the grid and the member 31,

and the lighter products passing over the member 32 of the discharge device.

During the next phase of the operation, that is during the ascending movement of the piston 5, the grid or sieve will be simultaneously raised and moved to the right, while the bulk of the bed settles on said sieve or grid.

When the discharge device is actuated in timed relation with the movements of the piston 5 through the connection 41—42, the common hinge 33 will be alternately raised and lowered, in concord with the lowering and raising movements of the sieve or grid 3, the discharge openings being increased in area when the sieve or grid is lowered and reduced in area when the sieve or grid is raised, thus promoting the discharge of the dense grains or particles towards the box and impeding their passage towards the discharge of the light products.

In carrying out the invention, the sieve or grid 3 is further arranged to receive various slopes and to this end either the links or rods 26 connecting the sieve or grid to the shafts 27 are formed as extensible members, or the ends of the shafts 27 are arranged to slide within elongated slots formed in the walls of the box 1 and serving as bearings for such shafts, or again the shaft 27 which is caused to oscillate and which, as illustrated, is the nearest to the entrance end of the sieve or grid 3, is mounted in fixed bearings and the other shaft 27 is journaled in rods or links 27a the angular position of which may be adjusted as desired relative to the driven shaft 27. To this end said rods or links 27a may be rigidly secured to a sleeve or sleeves 27b surrounding the said shaft 27 and arranged to be secured in a predetermined circular position on said shaft, by any suitable means such as a screw or its equivalent 27c.

Also the discharge end of the sieve or grid 3 is provided with an adjustable weir 3a, to which movements may be imparted in any desired manner, as for example by means of a screw like member 3b rotated by means of a gear operable from the outside and partly illustrated at 3c.

As pointed out in relation with the sieve or grid 3 shown in Fig. 1, a change in slope of the oscillating sieve or grid of Fig. 2 so as to reduce the ascending slope or to increase the descending slope towards the discharge end will enhance the advance of the materials on the sieve or grid and the discharge therefrom, especially of the dense portion of said materials, a reverse action taking place naturally should the change in slope be effected in the opposite direction.

As the adjustable weir 3a further enables a bed of any desired mean depth to be retained on the sieve or grid by the adjustment of said weir, variable slopes of the sieve or grid and movements of the plate 15, one may conform to the requirements the useful area and the working of the sieve or grid, that is the sorting or classifying as well as the advance and discharge of the material thereon.

According to yet another feature of the invention, means are provided in the box 1 enabling the respective actions on the materials occupying the sieve or grid 3, and on the discharge from said sieve or grid, of the liquid impulses and, or of the liquid currents, to be widely modified.

As illustrated, these means include a partition 44 extending the full width of the box 1 and dipping therein to a distance from its lower end or bottom, so as to provide kinds of compartments, one of which contains the sieve or grid 3 and the

other the discharge for said sieve or grid. The partition 44 includes, in addition to a fixed lower part 45 mounted on a shaft 46, an upper extensible part 47, for example formed by means of two plates arranged to be slideable relatively to each other, as by means of studs of one plate engaged in elongated slots of the other, one of said plates being secured to the shaft 46 and the other being hinged on a shaft 48 journaled in the frame 10 of the sieve or grid 3 and moving therewith. Within the space separating the lower edge of the partition 45 from the bottom of the box 1, is arranged an obturating member, such as a plate 49, securely fastened to a shaft 50 journaled in the walls of the box 1 and operable for turning movements from outside the box by means of any suitable drive, not shown. By changing the position of the plate 49 the sectional area of the passage between the compartments formed by the partition 44 may be modified, from the fully opened position to the fully closed position, or thereabout.

Instead of the arrangement just described, while retaining the upper portion of the partition 44 arranged as described above, the lower portion 45 may be rendered movable while retaining permanently a free passage between the lower edge of the partition and the bottom of the box, and arranging an obturating member mounted on and actuated by a shaft 50a, as illustrated in dotted lines at 49a, within the compartment of the box comprising the discharge from the sieve or grid 3.

Together with this latter arrangement, it may be useful to provide for an additional liquid supply 51 within the compartment comprising the discharge of the sieve or grid 3.

Whatever may be the adopted arrangement it will easily be seen that owing to this the liquid impulses and liquid currents generated by the piston 5 and the liquid supply 43 may be distributed within relatively wide limits between the compartments provided by the partition 44, according to the requirements for treating the materials on the sieve or grid 3 and at the discharge of said sieve or grid, observing that an increase in the mean depth of the materials on the sieve or grid 3, which increase requires a stronger action of the liquid impulses and liquid currents on these materials, corresponds precisely to a greater distance apart of the layers mainly comprising the dense products and the light products respectively and thus to a discharge of dense products having a relatively low content in light products which thence admits ascending currents of small or no value without giving rise to any substantial carrying of light products with the discharge dense products. Conversely a reduced depth of materials on the sieve or grid 3 requires a less marked action of the liquid impulses and liquid currents upon the materials occupying the sieve or grid, but to the contrary more stronger ascending currents acting on the discharge to avoid therein the carrying of light products with the dense products.

When the treated materials are mostly formed of grains or particles of small sizes, or show only a small content in dense products, it may be of interest to arrange the discharge in a different way, that is at a fixed location, distinct from the end of the sieve or grid, in order to enable a more accurate control of the conditions of passage to the discharge of the products to be evacuated.

In the exempliactive embodiment according to Fig. 3, suitable for such an application, the ar-

angement of the sieve or grid 3 proper may be similar to the sieve or grid arrangement of Fig. 1, that is with a mounting allowing for an adjustable slope of the sieve or grid about a shaft 11 provided with an appropriate drive for angular movement, as well as it may be similar to the sieve or grid arrangement of Fig. 2, that is with a mounting allowing for reciprocating movements of the sieve or grid, for example, as indicated in dotted lines, by means of the rods or links 26 securely fastened to shafts 27 journaled in bearings sliding in slots 27d of the box 1 and of which one at least is caused to oscillate.

The discharge of the evacuated materials is carried at a location such as 52; the discharge opening proper may be provided with movable and adjustable weirs as indicated at 53 and 54 and with this opening is associated a liquid supply 51 able to produce adjustable ascending currents adapted to prevent grains or particles the discharge of which is not desired to be carried to the discharge.

As shown in the figure, the box is additionally provided with a partition 44a the lower end of which leaves between itself and the bottom of the box a passage occupied at least in part by an obturating member in the form of a throttle valve or the like, as 49—50, a second partition 44b forming together with the partition 44a a kind of closed chamber which may conveniently serve to reduce the volume of the internal space of the box, and meeting or meeting approximately in the upper portion of the box 1, a hinge connection 55 formed between two members or plates 56 and 57 arranged in a bridge like manner between the end of the sieve or grid 3 and the discharge 52, said hinge connection being adapted for reciprocating movements in a vertical direction when the sieve or grid 3 is oscillated, and this in timed relation with the movements of the piston 5 as explained with reference to Fig. 2.

Naturally while retaining a distinct discharge 52, an arrangement other than the one just described could be devised, and for example only one partition such as 44a having a movable lower portion could be provided in association with a throttle valve or other obturator such as 49a, 50a arranged within the passage leading from the discharge 52 and preserved by the partition 44a as described with reference to Fig. 2.

As previously explained, the conditions for the treatment of the materials on the sieve or grid 3 and for the discharge at 52 could be modified in accordance with the requirements by judiciously acting on the various adjustable members or elements, observing that owing to the discharge 52 being separated, a widely greater independency is obtained for controlling the discharge conditions, enabling such discharge to be adjusted to allow for the sole discharge of products within very close limits of sizes and densities.

In the embodiment in accordance with Fig. 4, the sieve or grid 3 is arranged to receive variable slopes by means of a shaft, 11a located close to the sieve or grid end which is adjacent to the feed of the materials, and the other end of the sieve or grid is provided with a movable and adjustable weir such as 3a, the position adjustment of which is obtained by means of a screw or the like 3b. The sieve or grid arranged in this way is combined with a discharge taking place within a compartment of the box 1 provided by a partition such as 44a and controlled and, or regulated by means of a weir forming valve 58 adjustable

as to width and slope, as well as by means of liquid currents adjusted through a liquid supply 51 and an obturating device such as 49—50.

However, nothing prevents the sieve or grid 3 to be arranged in the manner described with reference to Fig. 2, that is so as to enable reciprocating movements thereof, the partition 44a then being arranged in either of the manners described for the partition 44 of Fig. 2.

Referring now to Fig. 5 in which one of the numerous applications of arrangements as previously described has been illustrated by way of example by the association of classing-separators, for example as in Fig. 2, with a washing trough in having the invention applied to the treatment of coals, it will be observed that in such a trough an extracting apparatus located upstream of the trough will have generally to perform the separation and the discharge of denser products, and this in more considerable quantities than an extracting apparatus located downstream in the trough. To be rational the extraction must take care of such depression in the specific weight and the quantity of the products to be extracted.

Owing to the invention such a condition may be entirely satisfied by means of a single type of apparatus.

As may be seen in the figure, showing three classing-separators associated with the washing trough 59 (the number of such classing-separators could be different from three), the parts or members of the upstream apparatus are adjusted to allow for the extraction of large quantities of very dense products, that is amongst other: the sieve or grid 3 is largely sloping, the weir 3a is largely raised, the plate 15 is advanced so as to reduce the useful surface of the sieve or grid and the obturator 50 (or the movable lower portion of the partition 44 and the obturator 49a, 50a) is adjusted in such a way that the liquid impulses and liquid currents act mainly on the materials occupying the sieve or grid 3.

To the contrary the parts or members of the downstream apparatus are adjusted to allow for the extraction of lesser quantities of lesser dense products, that is: the sieve or grid 3 receives a lesser slope, the useful surface of said sieve or grid is largely increased by a back shifting (towards the left) of the plate 15, the protuberance of the weir 3a is reduced or suppressed, and the obturator 49, 50 (or the movable lower portion of the partition 44 and the obturator 49a, 50a) is adjusted so that the liquid impulses and liquid currents may have a marked action on the discharge in order to prevent the discharge with the dense products of the light products to be retained into the trough 59.

The parts or members of the intermediate apparatus will receive adjustments intermediate between the above mentioned extreme adjustments, taking care of the particular conditions in the location of the apparatus and in the extraction to be effected.

Fig. 6 shows another application of the invention, that is to the ores the particles of which are of comparatively reduced sizes, for example diamond ores.

At 60 are shown concentrating apparatus called "pans" of which, until now, the concentrated products were treated in a series of drums to secure the separation thereof, in classes or categories within close limits of sizes, each class or category being subsequently treated in jigs or similar apparatus.

In accordance with the invention, the products

from the pans 60, after separation therefrom, if and when necessary, of the very fine particles—for example 0-1—and of the excess water—with in a drum not shown—are introduced into a washing trough 61 provided with one, two or a greater number of classing-separators, and yet more conveniently with one, two or a greater number of groups of two classing-separators according to Fig. 1, 3 or 4, designated 62 and illustrated as constructed in accordance with Fig. 1, the operation thereof being as indicated.

In operation, the concentrates from the first group are considered as finished products; the concentrates from the second group of classing-separators may be considered as finished products or, for one or both the apparatus of said group, as a product to be rewashed in which case they may be treated in separate apparatus and conveniently, for this purpose, received by a noria or other elevator 63 and returned to the head of the trough 61.

The discharge from the trough 61 is considered as tailings or may be subjected to a control treatment in suitable devices.

If desired the trough 61 and the associated apparatus may be mounted on a carriage to enable them to be easily combined with a movable plant such, for example, as the one partly illustrated.

Although the product from the pans 60 has been considered as the crude or starting product, said starting product could be a different one.

As already indicated the described embodiments and applications are exemplary only and not limitative ones, the invention including the modifications, the alternatives and the other applications.

I claim:

1. A jig for treating materials comprising grains or particles of different densities, such as coals, ores and the like, in variable quantities and variable compositions subjected to periodic liquid impulses, including a jig box adapted to have liquid therein to a predetermined level, means for producing pulsations in the liquid, a sieve pivotally supported in the upper portion of the jig box and spaced at its discharge end from the adjacent wall of the box to provide a discharge opening emptying into the portion of the box located below the sieve, adjustable means to set said sieve in a basic lengthwise position within an angle extending on either side of the horizontal, an adjustable weir at the discharge end of the sieve, adjustable discharge means positioned in the aforesaid discharge opening for controlling the effective area of said opening, and plate means for covering a portion of the length of the sieve surface to establish the useful working area of said surface.

2. A jig as in claim 1, in which the plate means for establishing the useful working area of the sieve includes a plate arranged to overlap a portion of the sieve at its feed end, and means for movably supporting the plate member to allow it to automatically accommodate different settings of the sieve.

3. A jig as in claim 1, in which the plate means for establishing the useful working area of the sieve includes a sloping plate arranged to overlap a portion of the sieve at its feed end, a movable guide member pivotally supporting the sloping plate to allow the latter to automatically accommodate different settings of the sieve, and a screw for moving the sloping plate and its guide member lengthwise of the sieve.

4. A jig for treating materials comprising

grains or particles of different densities, such as coals, ores and the like, in variable quantities and variable compositions subjected to periodic liquid impulses, including a jig box adapted to have liquid therein to a predetermined level, means for producing pulsations in said liquid, a sieve, at least one substantially horizontal cross shaft pivotally supporting the sieve, adjustable means to set said sieve in a basic lengthwise position within an angle extending on either side of the horizontal, at least one substantially horizontal oscillating cross shaft, link connections between said oscillating cross shaft and the sieve supporting shaft to impart oscillatory movements to the sieve in substantially parallel relation with said basic position, an adjustable weir and adjustable discharge means at the outlet end of the sieve, and means for covering the sieve surface on a continuous fraction of the length thereof to establish the useful working area of said sieve.

5. A jig for treating materials comprising grains or particles of different densities, such as coals, ores and the like, in variable quantities and variable compositions subjected to periodic liquid impulses, comprising a jig box adapted to have liquid therein to a predetermined level, a sieve supported in the upper portion of the jig box below the level of the liquid and terminating at its discharge end in spaced relation to the adjacent end wall of the box to provide a discharge opening, means for adjusting the angle of the sieve relative to the horizontal, a partition depending from the discharge end of the sieve to provide two passages in the box with one passage communicating with the sieve and the other passage communicating with the aforesaid discharge opening, means communicating directly with the passage for the sieve for pulsating the water in the jig box, an opening in the bottom of the jig box for discharging the materials that settle downwardly through the sieve and its passage and that settle downwardly through the aforesaid discharge opening and its passage, adjustable means cooperating with the partition and the adjacent wall of the jig box for controlling the extent to which the water in the passage communicating with the aforesaid discharge opening is affected by the action of the water pulsating means, and means for varying the effective area of the aforesaid discharge opening.

6. A jig as in claim 5, comprising means for oscillating the sieve through a given path while maintaining a given angle of adjustment of the sieve relative to the horizontal.

7. A jig as in claim 5, in which the said depending partition comprises a lower stationary section and an upper two-part section pivotally connected to the upper edge of the lower stationary section and to the discharge end portion of the sieve, and means for connecting the two parts of the upper section of the partition for relative sliding movements to accommodate different angular adjustments of the sieve.

8. A jig as in claim 5, in which means are provided for oscillating the jig through a given path while maintaining a given angle of adjustment of the sieve relative to the horizontal, and the said depending partition comprising a lower stationary section and an upper two-part section pivotally connected to the upper edge of the lower stationary section and to the discharge end portion of the sieve, and means for connecting the two parts of the upper section of the partition for relative sliding movements to accommodate dif-

ferent angular adjustments and oscillating movements of the sieve.

9. A jig for treating materials comprising grains or particles of different densities, such as coals, ores and the like, in variable quantities and variable compositions subjected therein to the action of liquid currents and periodic liquid impulses, including a jig box, liquid supply means for the box, mechanical means for producing pulsations in the liquid supplied to the box, driving mechanism for said mechanical means, a sieve, at least one substantially horizontal cross shaft for pivotally supporting the sieve, adjustable means to set said sieve in a basic lengthwise position within an angle extending on either side of the horizontal, an oscillatable mechanism operatively connected to said shaft to impart oscillatory movements to the sieve in substantially parallel relation with said basic position, an operative connection between the driving mechanism and the oscillatable mechanism to impart oscillating movements to the latter, an adjustable weir and discharge means at the outlet end of the sieve, movable members for adjusting said discharge means, an operative connection between said movable members and the oscillatable mechanism to actuate said movable members simultaneously with the operation of the oscillatable mechanism, and means for covering the sieve surface on a continuous fraction only of the length thereof to establish the useful working area of said sieve.

10. A jig as in claim 9, in which the operative connection between the movable members of the discharge means and the oscillatable mechanism includes means for adjusting the phase relation between the movements of the sieve and the movements of said movable members.

11. A jig for treating materials comprising grains or particles of different densities, such as coals, ores and the like, in variable quantities and variable compositions subjected therein to the action of liquid currents and periodic liquid impulses, including a jig box, liquid supply means for the box, a reciprocating piston, driving mechanism for reciprocating the piston, a sieve, at least one substantially horizontal cross shaft pivotally supporting the sieve, adjustable means to set said sieve in a basic lengthwise position within an angle extending on either side of the horizontal, at least one substantially horizontal oscillatable shaft, link connections

between said latter shaft and the sieve supporting shaft to permit oscillatory movements of the sieve in substantially parallel relation with the said basic position, an operative connection between the said driving mechanism and said oscillatable shaft to impart oscillating movements to the sieve in timed relation with the reciprocating movements of the piston, an adjustable weir and discharge means at the outlet end of the sieve, movable members for adjusting said discharge means, an operative connection between the said movable members and the oscillatable shaft to move said members in timed relation with the oscillated sieve and the reciprocated piston, means for covering the sieve surface on a continuous fraction only of the length thereof to establish the useful working area of said sieve, partition means extending generally upwardly through the box and forming therein compartments of which at least one includes the sieve and another includes the discharge, a communicating passage between said compartments, additional liquid supply means connected to the said compartments, and adjustable shutters in the said compartments to adjust the actions of the liquid impulses and liquid currents on the sieve and the discharge.

EDMOND HARVENGT.
